DESIGN FOR A CRUPPER

Charles W. Beck, Norborne, Mo.

Application May 9, 1941, Serial No. 100,861

Term of patent 14 years

To all whom it may concern:

Be it known that I, Charles W. Beck, a citizen of the United States, residing at Norborne, in the county of Carroll and State of Missouri, have invented a new, original, and ornamental Design for a Crupper, of which the following is a specification, reference being had to the accompanying drawing, forming a part thereof.

Fig. 1 is a perspective view of a crupper, showing my new design.

Fig. 2 is a side elevational view thereof; and
Fig. 3 is a top plan view thereof.

I claim:

The ornamental design for a crupper, as shown.

CHARLES W. BECK.
